CLAIM

(56) **References Cited**

The ornamental design for a food holder for a refrigerator door, as shown and described.

U.S. PATENT DOCUMENTS

DESCRIPTION

D483,046 S * 12/2003 Becke D15/89
D490,091 S * 5/2004 Quinlan D15/89
D494,195 S * 8/2004 Becke D15/89
D506,480 S * 6/2005 Floeter et al. D15/89
D511,177 S * 11/2005 Jackovin et al. D15/89
D511,179 S * 11/2005 Tunzi D15/89

FIG. 1 is a front, bottom and right side perspective view of the food holder for a refrigerator door showing our new design;

FIG. 2 is a right side view thereof, the left side view being a mirror image of the right side view;

FIG. 3 is a front view thereof;

FIG. 4 is a top view thereof; and,

FIG. 5 is a bottom view thereof.

The broken lines are for illustrative purposes only, and form no part of the claimed design.
